CLOCK RADIO

Samuel Frankel, 236 5th Ave., New York 1, N.Y.

Filed Apr. 24, 1962, Ser. No. 69,833

Term of patent 3½ years

(Cl. D56—4)

FIG. 1

FIG. 2

FIG. 3

FIG. 4

FIG. 5

FIGURE 1 is a front perspective view of a clock radio showing my new design;

FIGURE 2 is a side elevational view thereof, the side opposite being the same in appearance as the side shown;

FIGURE 3 is a top plan view thereof;

FIGURE 4 is a bottom plan view thereof; and

FIGURE 5 is a rear elevational view thereof.

The dominant features of my design reside in the portion shown in full lines.

I claim:

The ornamental design for a clock radio, as shown and described.
